UNITED STATES PATENT OFFICE.

HARRY F. KEEVER, OF NEW YORK, N. Y.

PROCESS OF EMBOSSED HAT LININGS OF FABRIC.

Application filed January 14, 1926. Serial No. 81,216.

To all whom it may concern:

Be it known that I, HARRY F. KEEVER, a citizen of the United States, and a resident of New York, in the county of New York 5 and State of New York, have invented a certain new and useful Process of Embossing Hat Linings of Fabric, of which the following is a full, clear, and exact specification.

This invention relates more particularly 10 to a class of die stamping or printing processes.

My invention has for its object primarily to provide a process of embossing especially 15 fancy designs, wording, and distinctive marks on hat linings of satin, silk and other fabrics in a manner whereby highly artistic and simpler effects in plain and combination colors may be accomplished, and which overcomes the objections to the present methods 20 in use wherein the stamping or printing material tends to spread by being absorbed by the threads of the fabric which in turn causes blurred and unsightly lines in the design.

The invention contemplates mainly the 25 steps which consist of stamping on the lining a background layer in one or more suitable colors of a selective design of adhesive material of a character which will not "run" 30 or spread in the texture of the fabric, in order to provide sharp and even contour lines of the design. On the background layer is printed by the use of a die a second selective design of preferably a color contrasting with the color of the background 35 layer, and a coating of meltable embossing compound is provided on the printed design. The printed lining is then subjected to heat 40 for melting the embossing compound for producing the design in a clear artistic effect.

With these and other objects in view, the 45 invention will be hereinafter more fully explained with reference to the accompanying drawing forming a part of this specification in which similar characters of reference indicate corresponding parts in all the views, and will then be pointed out in the claims at the end of the description.

In the drawing, Figure 1 is a fragmentary 50 view showing part of a hat lining on which is stamped a background layer according to my improved process.

Fig. 2 is a fragmentary view showing the

portion of the hat lining having the second 55 printing and embossing thereof as provided by the process, and

Fig. 3 is a fragmentary sectional view taken on the line 3—3 of Fig. 2.

In carrying into practice my process I 60 provide on a hat lining, as 10, of satin, silk or other fabric a background layer, as 11. This layer may be in the form of a selected plain or fanciful design, or wording or distinctive mark characteristic of the hats in 65 which the linings are to be used, and the layer is composed of meltable adhesive material which is stamped or impressed on the lining by the use of a heated metal die, not shown, having a stamping face of the 70 configuration of the background layer, as indicated in the line markings.

The background layer is preferable provided by being transferred from a sheet, such as paper which is coated with the adhesive 75 material, and an illustrative formula for making the transfer sheet consists of alcohol, approximately one pint by measure, powdered French white, approximately one-quarter pound by weight, powdered shellac, approximately one-quarter pound by weight, gum arabic, approximately one ounce by weight, and sufficient quantity of a pigment of suitable color. The ingredients are mixed 80 in the alcohol and thoroughly triturated by the use of appropriate means until the soluble ingredients are dissolved and until those which are insoluble are held in suspension. A liquid of semisirupy consistency will be provided, and a sufficient 85 quantity of the liquid is sprayed on one face of a sheet of paper of relatively tough texture to provide a coating of suitable thickness on the paper. The paper and its coating is then allowed to dry, and when subsequently used the paper is arranged with its 90 coated face in contact with the lining. The die is heated to a temperature sufficient for melting the coating to the required softness 95 so that when the die is impressed on the paper a sufficient quantity of the coating will be transferred to the lining which in turn will provide the background layer 100 11 on the lining by adhering to the texture of the lining material.

When dry the background layer will have a glossy varnish like appearance in the color corresponding to the color of the coating

of the transfer sheet. On the background layer 11 is then printed a second selected design, as 12, by employing a second die of the desired design which is used in conjunction with a suitable printing press or apparatus, and while the impression of the second selective design is still wet, an embossing compound such as the well known mixture of powdered resin and shellac is applied as a coating on the design. The lining with the coating of embossing compound is subjected to heat in a suitable machine for melting the compound to complete the process.

In the foregoing I have embodied the preferred form of my process, but I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:—

1. In a process of embossing hat linings of fabric, the steps which consist of stamping on the lining a background layer of adhesive material of a selected design, then printing on the background layer a second selected design by using a die, applying a coating of meltable embossing compound on the printed design and subjecting the printed lining to heat for melting the coating of embossing compound.

2. In a process of embossing hat linings of fabric, the steps which consist of stamping by a heated die on the lining a background layer of adhesive material of a selected design, then printing on the background layer a second selected design also by using a die, applying a coating of meltable embossing compound on the printed design and subjecting the printed lining to heat

for melting the coating of embossing compound. 45

3. In a process of embossing hat linings of fabric, the steps which consists of providing on the lining a background layer of adhesive material of a selected design by transferring the layer from a sheet coated with the transfer adhesive material, then printing on the background layer a second selected design by using a die, applying a coating of meltable embossing compound 55 on the printed design and subjecting the printed lining to heat for melting the coating of embossing compound.

4. A process of embossing hat linings of fabric, which consists of arranging on the lining a sheet coated with meltable transferring adhesive material, impressing on the sheet a heated die of a selected design for providing on the lining a background layer of the design of the die, then printing on the background layer a second selected design by using another die, applying a coating of meltable embossing compound on the printed design and subjecting the printed lining to heat for melting the coating of 70 embossing compound.

5. A process of embossing hat linings of fabric, which consists of arranging on the lining a sheet coated with meltable transferring adhesive material of a selected color, 75 impressing on the sheet a heated die of a selected design for providing on the lining a background layer, then printing on the background layer by using another die a second selected design in a color contrasting 80 from the color of the background layer, applying a coating of meltable transparent embossing compound on the printed design and subjecting the printed lining to heat for melting the coating of embossing compound. 85

This specification signed this 13th day of January A. D. 1926.

HARRY F. KEEVER.
